UNITED STATES PATENT OFFICE.

JAMES E. WORTH AND WILLIAM B. ETEN, OF FANCYHILL, VIRGINIA.

SPARKING DEVICE FOR ENGINES.

No. 811,470.

Specification of Letters Patent.

Patented Jan. 30, 1906.

Application filed May 15, 1905. Serial No. 280,636.

To all whom it may concern:

Be it known that we, JAMES E. WORTH and WILLIAM B. ETEN, citizens of the United States, residing at Fancyhill, in the county of 5 Rockbridge and State of Virginia, have invented a new and useful Sparking Device for Engines, of which the following is a specification.

This invention relates to sparking devices for internal-combustion engines, and has for its principal object to provide a novel means for properly timing the spark so that the engine may be run in either direction and the 10 sparking effected at the proper time without rendering it necessary to adjust the position of any of the members of the sparker proper.

A further object of the invention is to provide a mechanism which in adjusting the time of operation of the sparking device may 15 be employed as a means for reversing the direction of rotation of the crank-shaft.

With these and other objects in view, as will 20 more fully hereinafter appear, the invention consists in certain novel features of construction and arrangement of parts hereinafter 25 fully described, illustrated in the accompanying drawings, and particularly pointed out in the appended claims, it being understood that various changes in the form, proportions, size, 30 and minor details of the structure may be made without departing from the spirit or sacrificing any of the advantages of the invention.

In the accompanying drawings, Figure 1 is a 35 side elevation of sufficient of an internal-combustion engine to illustrate the application thereto of a sparking device constructed in accordance with the invention, the crank-shaft being shown in section. Fig. 2 is a side 40 elevation of the same. Fig. 3 is a detail view of the sparking mechanism looking from the interior of the explosion-chamber.

Similar numerals of reference are employed 45 to illustrate corresponding parts throughout the several figures of the drawings.

The working parts of the engine include the cylinder A and crank-shaft B, the latter being connected to a counter-shaft C by reducing-gearing D, as usually practiced in four- 50 cycle engines.

Passing through the wall of the explosion-chamber is a rock-shaft 10, carrying at its inner end an electrode 11, which may be moved into engagement with a second electrode 12, 55 these two electrodes being electrically connected in a circuit 13, including a source of

electrical energy and a sparking coil. Surrounding the rock-shaft is a spring 14, one end of which bears against a fixed pin 15 and the other against the electrode 11, the spring 60 serving to maintain the said electrode 11 in engagement with a stop 16.

To the outer end of the rock-shaft 10 is secured a gear 19, carrying a radially-projecting arm 20, that preferably is formed of yieldable material—as, for instance, a strip of spring-steel—and with this arm engages the upper end of a rod 21, the lower end of which is secured to a strap 22, encircling an eccentric 23 on the counter-shaft C, and each time 70 the shaft C is rotated the eccentric-rod will be moved up until the head of the rod elevates the arm 20 to an extent sufficient to move the electrode 11 into engagement with the electrode 12, further movement causing the head 75 of the rod to pass beyond the arm 20, whereupon the spring 14 rapidly moves the rock-shaft in the opposite direction and by separating the electrodes creates a spark.

Secured to the cylinder or other fixed portion of the engine is a guide 25, arranged for the reception of a slideable block 26, that carries a pivotally-mounted guide 27, through which the rod 21 passes, and as the rod is reciprocated longitudinally the guide 27 will be 85 turned on its pivot to accommodate the variable angle of the lower end of the rod due to its connection with the eccentric.

Mounted on a stud 30, that projects from the wall of the explosion chamber or cylinder, 90 is a gear 31, carrying a radially-projecting arm 32, also preferably formed of spring-steel adapted to be engaged by the head of the rod 21 when the engine is running in the reverse direction. Under normal conditions the 95 gear 31 and arm 32 move idly, owing to the connection with the gear 19, and when the outer portion of the rod 21 is shifted to the dotted-line position shown in Fig. 1 the arm 32 will be engaged by the head of the rod and 100 the movement will be transmitted, through the gears 31 and 19, to the rock-shaft 10. In order to accomplish the adjustment of the rod 21, a bell-crank lever 33 has one arm connected to the slide-block 26, and its opposite 105 arm carries a bolt 34, that may travel in an arcuate slot 35, formed in a bar 36, secured to the cylinder or otherwise rigidly supported, the connection being such that the reversing-lever 33 may be locked in any position 110 to which it is adjusted, and by effecting close adjustment the time of the spark may

be altered to some extent—that is to say, the head of the rod 21 may be so adjusted as to leave either the arm 20 or the arm 32 at the full stroke of the eccentric or slightly before the full stroke of the eccentric.

When the engine is running in one direction, the parts are arranged as shown in full lines in Fig. 1. To reverse, it is desirable, but not always necessary, to cut off the supply of fuel and allow the engine to slow down until on a compression-stroke there is just sufficient momentum to carry the piston to the top of the cylinder. The slide-block 26 is then shifted from the position shown in the full lines in Fig. 1 to the position shown in dotted lines, this occurring before the piston has moved fully up, so that as the piston moves up on the compression-stroke the head of the rod will engage the arm 32 and move the electrode 11 into engagement with the electrode 12, and then just before the completion of the compression-stroke the electrodes will be separated and the spark will occur, effecting rotative movement of the shaft in the opposite direction.

Having thus described the invention, what is claimed is—

1. The combination in a sparker, of a pair of electrodes, one of which is movable, a rock-shaft carrying the movable electrode, a yieldable arm connected to the rock-shaft, a second shaft, also having a yieldable arm, means for connecting the two shafts, and an operating-rod adjustable to engage one or other of said arms.
2. The combination with a sparker including a rock-shaft carrying one of the electrodes, a gear secured to the rock-shaft, a yieldable arm extending from the gear, a second gear intermeshing with the first and also having a yieldable arm, and an operating-rod adjustable to engage one or other of said arms.
3. The combination in a sparker, of a rock-shaft carrying one of the electrodes, a gear

secured to the rock-shaft, a yieldable arm 45 projecting from the gear, a second gear engaging the first and also having a yieldable arm, a rod operated from the engine, and a rod-guide adjustable to direct the rod into engagement with one or other of the arms. 50

4. In a sparker, a rock-shaft, a gear connected thereto, an arm extending from the gear, a second gear intermeshing with the first and provided with an extending arm, an endwise-movable rod operable from the engine, a guiding member for said rod, and means for adjusting the position of said guiding member to direct the rod into engagement with one or other of the arms. 55

5. The combination in a sparker, of a rock-shaft, an electrode carried thereby, a gear-wheel connected to the rock-shaft, an arm extending from the gear, a second gear intermeshing with the first and also having an extending arm, an endwise-movable rod operated from the engine, a guide, a slideable block mounted thereon, and a pivotally-mounted rod-guiding member connected to said block. 65

6. The combination in a sparker, of a rock-shaft, an electrode connected thereto, a gear secured to the rock-shaft, an arm extending from the gear, a second gear intermeshing with the first, and also provided with a projecting arm, an endwise-movable rod operated from the engine, a guide, a slideable block mounted therein, an adjusting-lever connected to said block, means for locking the adjusting-lever in position, and a pivotally-mounted rod-guiding member carried by said block. 75

In testimony that we claim the foregoing as 80 our own we have hereto affixed our signatures in the presence of two witnesses.

JAMES E. WORTH.
WILLIAM B. ETEN.
